(57) **CLAIM**

The ornamental design for a mirror reinforcement device, as shown and described.

DESCRIPTION

FIG. 1 is a perspective view of a mirror reinforcement device;

FIG. 2 is an opposing perspective view thereof;

FIG. 3 is a right side elevation view thereof;

FIG. 4 is a left elevation side view thereof;

FIG. 5 is a top plan view thereof;

FIG. 6 is a bottom plan view thereof;

FIG. 7 is a back elevation view thereof; and,

FIG. 8 is a front elevation view thereof.

In the drawings, the evenly-spaced broken lines depict portions of the article that form no part of the claimed design.
